OTHER PUBLICATIONS

Prior art design of water distillation unit on sale more than one year before the filing date of this application.

Primary Examiner—Robin V. Taylor
Attorney, Agent, or Firm—Van Dyke, Gardner, Linn & Burkhardt, LLP

[57] CLAIM

The ornamental design for the water distillation unit, as shown and described.

DESCRIPTION

FIG. 1 is a front, top and left end perspective view of a water distillation unit according to the invention;

FIG. 2 is a front elevation thereof;

FIG. 3 is a top plan view thereof;

FIG. 4 is a rear elevation thereof;

FIG. 5 is a right end elevation thereof;

FIG. 6 is a left end elevation thereof; and,

FIG. 7 is a bottom plan view thereof.

The broken line showing in FIG. 4 is for illustrative purposes only and forms no part of the claimed design.
